[57] CLAIM

The ornamental design for a bottle or similar article, as shown and described.

DESCRIPTION

FIG. 1 is a front elevational view of a bottle or similar article showing my new design.

FIG. 2 is a rear elevational view.

FIG. 3 is a top plan view; and

FIG. 4 is a bottom plan view.

The right side and left side elevational views, not shown, are similar to FIG. 2.
